INTERNAL COMBUSTION MOTOR

George F. Callahan, Jr., Mount Lebanon, Pa.

Application February 20, 1936, Serial No. 64,869

17 Claims. (Cl. 123—122)

This application is a continuation in part of my copending application Serial Number 20,527 filed May 9, 1935 for Internal combustion motor.

The invention pertains to internal combustion motors and particularly to the arrest and regulation of heat, which is given off by the exhaust manifold, consumed by the air intake manifold and consequently united with the combustion fuel. In the case of motor vehicles where the internal combustion motor lies encased, beneath the hood of the vehicle, the temperature of the air consumed by the intake manifold depends largely upon the underhood temperature. It has been found that during the summer months this under-hood temperature has been in excess to that required for the proper vaporization of the combustion fuel; while during the winter season this underhood temperature is insufficient thereby detrimentally decreasing the efficiency of the internal combustion motor. Furthermore, in certain sections of the country where the terrain is of varying altitudes the underhood temperature is constantly changing. It is the present practice, among the automotive industry, to strike a medium between these varying underhood temperatures and adjust the internal combustion motor for the mean temperature. By this present practice it will be readily observed that the temperature of the air consumed by the intake manifold will vary considerably above and below the range of degree required for the proper vaporization of the combustion fuel.

One of the objects of the present invention is the provision of a mechanism whereby the temperature of the air, drawn into an internal combustion motor, may be positively controlled to within a narrow range of degree.

Another object of the invention is the provision of a jacket arranged to encase the air cleaner and partially encase the exhaust and intake manifolds of an internal combustion motor.

A further object of the invention is the provision of a tubular member extending outwardly of the jacket beyond the front wall thereof to a position adjacent the radiator fan in order to direct a column of relatively cold air into the jacket.

A still further object of the invention is the provision of means whereby the temperature of the air within the jacket may be regulated either manually or thermostatically.

These and other objects will become apparent to those skilled in the art by referring to the accompanying drawings which illustrate the embodiment of the present invention, wherein:

Figure 1 represents a vertical elevation of an internal combustion motor embodying the present invention.

Figure 2 represents a portion of the plan view of the disclosure of Figure 1.

Figure 3, an enlarged sectional view taken along the lines 3—3 of Figure 2, shows the arrangement of the shutters and tubular member employed to assist in regulating the temperature of the air within the jacket.

Figure 4, an enlarged sectional view taken along the lines 4—4 of Figure 2, shows the thermostatic mechanism and its connection to the shutter arrangement.

Figure 5, an enlarged view taken along the lines 5—5 of Figure 2, shows the manually operating mechanism and its connection to the shutter arrangement.

Figure 6, an enlarged view taken along the lines 6—6 of Figure 1, shows an auxiliary door in the rear wall of the jacket as well as an end view of the thermostatic operating mechanism.

Figure 7 showing a modification of the invention is taken along a line similar to 3—3 of Figure 2 excepting that the rear wall of the jacket is shown.

Figure 8 shows, in front elevation, a modification of the thermostatic mechanism and its connection to the shutter arrangement.

Figure 9 shows a side elevational view of the structure disclosed by Figure 8.

Figure 10 is a sectional view taken along the lines 10—10 of Figure 9.

Referring now in detail to the drawings wherein like numerals indicate similar parts, the internal combustion motor, generally designated as at 1, has a substantially horizontal exhaust manifold 2 extending longitudinally of the motor toward the front portion thereof and thence downwardly, as at 3, toward the muffler (not shown). The intake manifold 4, spaced beneath the exhaust manifold, has a portion 4a extending in a substantially vertical direction outwardly of, and through the horizontal plane of, the exhaust manifold 2. The air intake portion 4a of the intake manifold 4 supports the air cleaner 5 above the horizontal plane of the exhaust manifold and conducts the air, employed to vaporize the combustion fuel, to the carburetor 6. The air intake has an angular portion 4b adjacent the air cleaner 5. The usual radiator fan 7 is located adjacent the front portion of the internal combustion motor 1 immediately in back of the radiator 8.

The jacket 9, employed to arrest the heat radiating from the horizontally disposed portion of

5

the exhaust manifold 2, includes an inner wall 10 and an outer wall 11 both of which extend vertically from a plane adjacent the lower portion of the exhaust manifold 2 to a position preferably above the air cleaner 5. The inner wall 10, located between the exhaust manifold and the motor casing, and the outer wall 11 positioned outwardly of the exhaust manifold and passing through the plane of the air intake at the angular portion 4b, are of sufficient horizontal dimensions so as to overly an appreciable length of the exhaust manifold. Hoods 16a are provided in the inner wall to straddle the ports 2a of the exhaust manifold 2.

15 The top wall 12 of the jacket 9 has an upper portion 12a spaced above the air cleaner 5, a downwardly projecting intermediate portion 12b and a substantially horizontal lower portion 12c spaced above the exhaust manifold 2 connecting the upper edges of the inner and outer walls. The lower portion 12c of the top wall together with the inner and outer walls 10 and 11 respectively merge adjacent the front portion of the jacket to form the front wall 13. The rear wall 14, extending between and secured to the upper portion 12a of the top wall, inner wall 10 and outer wall 11, forms a closure for the rear portion of the jacket. The band 15 employed to secure the flange 16, projecting outwardly of the front wall 13, to the exhaust manifold while the clips 17, extending outwardly of the valve cover 1a, are secured to the inner portion of the jacket. Thus the band 15 and the clips 17 retain the jacket in position. It will be observed from the preceding description that the jacket 9 forms a complete enclosure for the air cleaner 5 and a partial enclosure for the exhaust manifold 2 and intake manifold 4. With the present arrangement the jacket will arrest an appreciable amount 40 of heat radiating from the exhaust manifold in order to permit said heat to pass through the air cleaner into the air intake and thence to the carburetor, intake manifold and mixing chamber.

So as to allow the ingress of cold air within the jacket 9 an opening 18 is provided preferably in the downwardly projecting intermediate portion 12b of the top wall 12. The shutter arrangement 19, mounted upon the portion 12b of the top wall comprises vertically spaced Z-shaped closing pieces 20 and horizontally spaced angular members 20a secured together to form a box-like frame extending around the opening 18 and projecting outwardly of the plane of the top wall 12b. A plurality of plates 21, spaced at convenient intervals and extending between the angular members 20a, are secured to the bars 22 and 22a and, in normal or closed position, arranged in overlapping relation to each other and the closing pieces 20. Thus the plates 21 together with the closing pieces 20 and angular members 20a form a closure for the opening 18. The bars 22 and 22a are pivotally mounted in and extend through the angular members 20a. Adjacent to the one side of the shutter arrangement, inwardly of the jacket, is an operating lever 23 pivotally connected to a plurality of links 24 which extend outwardly of and are secured to adjacent ends of the bars 22 and 22a.

70 It will be observed by referring to Figure 3 of the drawings that when the operating lever is moved in a substantially vertical direction the links 24, bars 22 and 22a will rotate in a counter-clockwise direction thereby forcing the plates 21 to assume a horizontal or open position and al-

lowing the ingress of relatively cold air within the jacket 9.

During some periods or unusual conditions of operation the underhood temperature may be in excess to that required for the proper vaporization of the combustion fuel and with this in mind a tubular member 25 has been provided in order to arrest relatively cold air entering beneath the hood immediately as it passes through the radiator 8. The tubular member 25 is removably secured to the upper portion 12a of the top wall, inner wall 10 and outer wall 11 and extends outwardly of the downwardly projecting portion 12b of the top wall. The tubular member 25, forming a hood around the shutter arrangement, projects horizontally beyond the plane of the front wall 13 to a position in spaced relation and adjacent to, the radiator fan 7. By this arrangement a column of relatively cold air is directed toward the shutter arrangement before it has an opportunity to mix with the heated air beneath the hood.

15 An opening 26 is provided in the rear wall 14 of the jacket adjacent the top portion thereof in order that a direct current of air may pass 25 through the top portion of the jacket thereby materially assisting in quickly lowering the temperature of the air within the jacket. The cover 27, hingedly connected to the rear wall and serving as a closing piece for the opening 26, is retained in closed position by the catch 28.

30 In order to control the movement of the shutter arrangement a manual and thermostatic mechanism has been provided. During extremely cold weather it may be desired to retain the shutters 35 in closed position for a period of time after the thermostatic mechanism has begun to open the shutters so that a quicker motor warm-up will be affected. The manual controlling mechanism is therefore arranged to retain the shutters in 40 closed position. The lever 29 extending upwardly of the bar 22a is secured to the bar 22a outwardly of the vertical plane of the inner wall 10. A sleeve 30 is pivotally secured to the lever 29 adjacent the upper end thereof. A toggle lever 31, pivotally mounted in a suitable bracket 32 located on the instrument panel 33, is slideably connected to the sleeve 30 by means of the compression member 34. Block 35 is secured to the compression member 34 intermediate the ends thereof and conveniently spaced from the sleeve 30. It will be observed by referring to Figure 5 of the drawings that when the handle portion 31a of the toggle lever 31 is moved downwardly the extension 31b of the lever 31 will carry the block 35, by means of the compression member 34, toward as well as through the sleeve 30, until the block 35 has come to rest against the sleeve. By this manually operated mechanism it will be noted that the shutter arrangement can be retained in closed position.

35 The portion 4b of the air intake being angularly inclined through the outer wall 11 of the jacket, preferably immediately beneath the air cleaner 5, is tubular in cross-section having an outer wall 36. A thermostat 37, of a suitable range, is positioned entirely within the air intake thereby allowing the air traveling through the air intake to pass over the thermostat. The thermostat is supported by the plate 38 which is 45 secured to the outer wall 36 of the intake manifold and having gaskets therebetween to prevent the transmission of heat from the plate 38 to the thermostat. The horizontally disposed rod 39, pivotally mounted in the bracket 40, extends 50

through one side of the air intake and is pivotally connected to the thermostat by the horizontally disposed lever 41. The bracket 40 is located preferably above the thermostat within the air intake and is also supported by the plate 38. Located between the air intake and the outer wall 11 of the jacket is a vertically disposed lever 42 secured to the rod 39 adjacent the end thereof. The arm 43 is secured to the bar 22a outwardly 10 of the vertical plane of the outer wall 11 of the jacket and has a swivel nut 44 pivotally mounted adjacent the lower end thereof. Pivotally connected to the vertically disposed lever 42 is a connecting rod 45 extending outwardly of the 15 lever 42 and projecting through the swivel nut 44. A compression spring 46, provided on the connecting rod, abuts the swivel nut 44 and a shoulder 47 which is formed on the connecting rod intermediate the ends thereof. The compression spring 46 and the slidable support of the connecting rod by the swivel nut thus forms a variable connection between the thermostat 20 and shutter arrangement.

In order to prevent an accidental excess amount 25 of heated air to pass over the thermostat 37 which would result in the rupture of one or more of its convolutions an aperture 48 has been provided in the outer wall of the air intake preferably adjacent and above the thermostat. The door 49, 30 hinged to the outer wall of the air intake, is of sufficient dimensions to cover the aperture 48 and is retained in normal or closed position by means of a spring 49a or any desirable means. The extension 41a on the horizontally disposed 35 lever 41 is so arranged that it will force the door 49 open after the shutter arrangement 19 has reached its fully opened position thereby allowing relatively cold air to enter the intake manifold through the aperture 48 and pass over the 40 thermostat.

The operation of the thermostatic mechanism is as follows: Assuming the temperature of the air within the jacket has begun to reach a degree in excess to the amount required for the 45 proper vaporization of the combustion fuel and the block 35 of the manual operating mechanism is spaced from the sleeve 30. The heated air within the jacket 9 traveling through the air cleaner 5 and portions 4a and 4b of the air intake 50 will pass over the convolutions of the thermostat 37 thereby forcing the thermostat to expand in a vertical direction. This movement of the thermostat will impart a clockwise motion to the horizontally disposed lever 41, rod 39 and vertically disposed lever 42. The clockwise motion 55 of the lever 42 will force the connecting rod 45 in a horizontal direction and, through the compression spring 46, the arm 43 and bar 22a will rotate in a counter-clockwise direction thereby 60 forcing the plates 21 of the shutter arrangement into a horizontal or open position.

It will be observed that if the manual operating mechanism is set to retain the shutter arrangement in closed position the connecting rod 45 of the thermostatic mechanism will pass through the swivel nut 44 as the variation between the lever 42 and swivel nut 44 will be absorbed by the compression spring 46. By this arrangement it will be further observed that the 65 thermostat is permitted to operate without adding any undue strains to its convolutions.

Figures 7 to 10 both inclusive disclose a modification of the present invention. The jacket 51 is somewhat similar to the jacket 9, shown by 70 Figures 1 to 6, in construction excepting that an

additional shutter arrangement 52 is mounted on the rear wall 53 of the jacket and is adapted to serve as a cover for the opening 53a. The shutter arrangement 52 as well as the shutter arrangement 54, which is mounted on the intermediate portion 55b of the top wall 55, are preferably the same in construction as the shutter arrangement 19 shown by Figure 3.

The bar 56 of the shutter arrangement 52 extends outwardly of the jacket and has secured thereto, adjacent the extremity thereof, a downwardly projecting lever 57. An upwardly extending lever 58 is secured to the bar 59, outwardly of the jacket, and pivotally connected to the lever 57 by means of the connecting rod 84. 15 It will be observed that when the bar 59 and lever 58 rotate in a counter-clockwise direction the connecting rod 84 will move in a substantially horizontal direction thereby forcing the lever 57 and bar 56 to rotate in a clockwise direction. 20 This movement of the bars 56 and 59 will force the plates 60 to assume a substantially horizontal or open position through the links 61 and operating levers 62. The operation of the shutter arrangements 52 and 54 will be simultaneous 25 and, in open position, provide passage for a current of air through the top portion of the jacket encasing the air cleaner 5 thereby affecting an immediate change in the temperature of the air to be consumed by the air intake. 30

The thermostatic operating mechanism connected to the shutter arrangements 52 and 54 respectively comprises a unit 63 forming a portion of the air intake 4a. It will be noted from the following description that when the degree 35 of heated air passing through the air intake nears or reaches an excessive degree a means has been provided to gradually or completely cut off the source of air supply from within the jacket and allow the air intake to consume air from beneath the hood or any desirable source. The mechanism is so arranged so as to provide a gradual change-over of air thereby allowing the proper temperature of air to enter the air intake under all conditions. 40

The unit 63 includes a housing 64 located 45 preferably adjacent the angular portion 4b of the air intake 4 which, in addition to forming a duct for the passage of air to the carburetor 6, encases the thermostatic mechanism. Suitable collars 65 extending outwardly of the housing are secured to the portion 4a of the air intake. A removably secured cover 66 forms the front portion of the housing 64 and functions as a support for the portion of the mechanism within the housing thereby allowing the major portion of the mechanism to be assembled thereon and placed into the housing as a unit. The thermostat 67, of a suitable range and adapted to move in a vertical direction, is governed by the 50 temperature of the air passing over the convolutions thereof. Angular plate 68, supporting the thermostat, is secured to the cover 66 and projects inwardly of the housing. An inverted channel shaped bracket 69, secured to the cover 66 and spaced above the thermostat 67 and plate 68, pivotally supports the rod 70 which has a portion 70a extending through the housing 64. The arm 71, pivotally connecting the thermostat to the rod 70, is secured to the rod 70 intermediate the ends thereof. A downwardly extending lip portion 72 projects from the arm 71. 55

Secured to the portion 70a of the rod 70 is a substantially vertical lever 73 which is moved radially about the rod 70 as a result of the vari- 60

ation in length of the thermostat 67. The arm 43a is secured to the bar 59, outwardly of the jacket 51, and has a swivel nut 44a pivotally attached to the one end thereof. Pivotally connected to the lever 73 and slideably connected to the swivel nut 44a is a connecting rod 45a having a shoulder 47a formed thereon intermediate the ends thereof. The compression spring 46a, retained in position by the connecting rod 45a, abuts the shoulder 47a and the swivel nut 44a. It will be observed from the immediate preceding description that when the length of the thermostat increases or diminishes the pivotal movement of the arm 71 and rod 70 will impart a radial movement to the lever 73 and arm 43a. This movement will create a pivotal action in the bar 59 thereby causing the shutter arrangements 52 and 54 to open or close.

An aperture 74 in the housing 64 is located preferably above the horizontal plane of the thermostat and is provided with a closing plate 75 hinged, adjacent the lower portion thereof, to the housing. The closing plate is retained in normal or closed position by means of a spring 76 or any other suitable means. The purpose of the aperture 74 is to allow the ingress of relatively cold air within the housing 64 thereby passing over the thermostat and preventing the rupture of one or more of the convolutions of the thermostat. The entrance of relatively cold air through the aperture 74 will also assist in maintaining the desired temperature of the air to be mixed with the combustion fuel.

The step 76 secured to the closing plate projects inwardly of the housing and overlies the lip portion 72 of the arm 71 in spaced relation. A butterfly valve 77 is pivotally mounted within the portion 4a of the air intake on the diametrical center thereof and is positioned above the horizontal plane of the aperture 74. An arm 78 extends outwardly from one side of the butterfly valve 77. The butterfly valve controlling link 79 is pivotally connected to the arm 78 and bracket 80 which is secured to the closing plate 75 inwardly of the housing.

When the temperature of the air passing through the air intake nears a degree in excess to that required for the proper vaporization of the combustion fuel the length of the thermostat 67 will increase and result in the upward movement of the lip portion 72 of the arm 71. In this upward movement the lip portion 72 will engage the step 76 thereby forcing the closing plate 75 away from the housing and allowing the relatively cold air to enter the housing through the aperture 74. The outward movement of the closing plate 75 will, through the controlling link 79, rotate the butterfly valve in a counter-clockwise direction which will reduce the cross-sectional area of the air intake at this location and consequently decrease the amount of heated air entering the housing. The mechanism is so arranged that the heated air entering the housing from the jacket 51 can be cut off completely while relatively cold air may be drawn into the housing through the aperture 74.

A removably secured hood 81 is provided on the one side of the housing functioning as a protective shield for the closing plate 75 as well as a guard against foreign matter entering the air intake. The opening 82 in the lower portion of the hood has a downwardly projecting flange 83 formed along the periphery thereof to which may be attached an additional air cleaner (not shown). If it is so desired a tubing made to

extend to a position outwardly of the hood of the vehicle may be attached to the flange 83.

It will, of course, be understood by those skilled in the art that various alterations may be made to the precise construction as shown by the accompanying drawings and described in the present specification without departing from the scope of the appended claims.

Having thus described the invention what I claim as new and desire to secure by Letters Patent is:

1. In an internal combustion motor, in combination, an exhaust manifold, an air intake, an air cleaner supported by said air intake, a jacket enclosing the air cleaner and partially encasing said manifold and air intake, said jacket having a shutter arrangement for selectively regulating the temperature within the jacket, means within the air intake spaced beneath the air cleaner, and a resilient connection between said means and shutter arrangement adapted to operate the shutter arrangement.

2. In an internal combustion motor, in combination, an exhaust manifold, an air intake having an outer wall, and a jacket partially encasing said manifold and air intake; said jacket having a shutter arrangement for selectively regulating the temperature within the jacket, thermostatic means within said air intake connected to the shutter arrangement, a door pivotally secured to the outer wall of the air intake adapted to close an aperture in said outer wall, and a lever connected to said thermostatic means adapted to open said door.

3. In an internal combustion motor, in combination, an exhaust manifold, an air intake having an outer wall, and a jacket partially encasing said manifold and air intake; said jacket having a shutter arrangement for regulating the temperature within the jacket, a door pivotally secured to the air intake adapted to close an aperture in the outer wall of the air intake, and a thermostatic means within the air intake adapted to operate the shutter arrangement and open the door.

4. In an internal combustion motor, in combination, an exhaust manifold, an air intake having an outer wall, and a jacket partially encasing the manifold and air intake; said jacket having a shutter arrangement for regulating the temperature within the jacket, a door pivotally secured to the air intake adapted to close an aperture in the outer wall of the air intake, and thermostatic means within the air intake adapted to open and close the shutter arrangement and open the door after said shutter arrangement has been opened.

5. In an internal combustion motor, in combination, an exhaust manifold, an air intake, and a jacket partially encasing the exhaust manifold and air intake; said jacket having a shutter arrangement adapted to selectively regulate the temperature within the jacket, a thermostatic mechanism within the air intake, a bar extending through the air intake and connected to the thermostatic mechanism, and a resilient means connecting the shutter arrangement and bar.

6. In an internal combustion motor, in combination, an air intake, a housing forming a portion of the air intake, a closing plate adapted to cover an aperture in said housing, a butterfly valve pivotally mounted within the housing above the horizontal plane of the aperture, and thermostatically controlled means within the housing adapted to control the movement of said closing plate and butterfly valve.

7. In an internal combustion motor, in combi-

5 nation, an air intake, an air cleaner secured to the air intake, a housing forming a portion of the air intake spaced below the air cleaner, a closing plate adapted to cover an aperture in said housing, a butterfly valve pivotally mounted within the housing above the horizontal plane of the aperture and pivotally connected to the closing plate, and a thermostatically controlled means within the housing adapted to control the 10 movement of said closing plate and butterfly valve.

8. In an internal combustion motor, in combination, an exhaust manifold, an air intake, an air cleaner supported by the air intake, a jacket 15 encasing the air cleaner and partially encasing the exhaust manifold and air intake, said jacket having a shutter arrangement for selectively regulating the temperature within the jacket, thermostatic means within the air intake adapted to operate said shutter arrangement, and a manually operated mechanism adapted to retain the shutters in closed position.

9. In an internal combustion motor, in combination, an exhaust manifold, an air intake, and 25 a jacket partially encasing said manifold and air intake, said jacket having a shutter arrangement for selectively regulating the temperature within the jacket a thermostatic mechanism within the air intake, and a resilient means connecting 30 said shutter arrangement and thermostatic mechanism.

10. In an internal combustion motor, in combination, an air intake, a housing forming a portion of the air intake, a closing plate hingedly secured to the housing and adapted to cover an aperture in said housing, a butterfly valve pivotally mounted within the housing, and thermostatically controlled means within the housing adapted to control the movement of said closing 40 plate and butterfly valve.

11. In an internal combustion motor, in combination, an air intake, a housing forming a portion of the air intake, a closing plate hingedly secured to the housing adapted to cover an aperture in said housing, a butterfly valve pivotally mounted within the housing and pivotally connected to the closing plate, and thermostatically controlled means adapted to control the movement of the closing plate and butterfly valve.

50 12. In an internal combustion motor, in com-

bination, an air intake, a housing forming a portion of the air intake, a closing plate adapted to cover an aperture in said housing, a step secured to the closing plate inwardly of the housing, a butterfly valve pivotally mounted within the housing and connected to the closing plate, and thermostatically controlled means adapted to engage said step to control the movement of the closing plate and butterfly valve.

13. In an internal combustion motor, in combination, an exhaust manifold, an air intake, a jacket partially encasing said manifold and air intake, said jacket having a shutter arrangement for selectively regulating the temperature within the jacket, thermostatic means mounted within the air intake, and a variable connection outwardly of the air intake extending between the thermostatic means and shutter arrangement.

14. In an internal combustion motor, in combination, an air intake, a housing forming a portion of said air intake, an aperture in said housing, a door secured to said housing adapted to cover said aperture, a butterfly valve in the air intake, and thermostatically controlled means within the air intake adapted to operate said butterfly valve and door.

15. In an internal combustion motor, in combination, an air intake, a jacket partially encasing said air intake, a shutter mounted on the jacket, thermostatically controlled means within the air intake slidably connected to the shutter adapted to operate said shutter, and manually operated means connected to said shutter for preventing said shutter from opening.

16. In an internal combustion motor, in combination, an exhaust manifold, an air intake, a jacket partially encasing said manifold and air intake, means on said jacket for regulating the temperature of the air within the jacket, and a thermostatically controlled mechanism resiliently connected to said means.

17. In an internal combustion motor, in combination, an air intake, a jacket partially encasing said air intake, a shutter mounted on said jacket, a thermostat within the air intake, means pivotally connected to the thermostat and resiliently connected to the shutter adapted to open the shutter, and a manually operated means for retaining said shutter in closed position.

G. F. CALLAHAN, JR. 50
